UNITED STATES PATENT OFFICE.

FREDERICK A. HART, OF NEWARK, NEW JERSEY, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,302,159.

Specification of Letters Patent.

Patented Apr. 29, 1919.

Application filed April 5, 1916. Serial No. 88,982.

To all whom it may concern:

Be it known that I, FREDERICK A. HART, a citizen of the United States, residing in Newark, in the county of Essex and State 5 of New Jersey, have invented certain new and useful Improvements in Combined Type-Writing and Computing Machines, of which the following is a specification.

This invention relates to computing machines, or combined typewriting and computing machines, and more particularly to means whereby the pointing off or spacing between figures, as between dollars and cents, and between hundreds and thousands, 10 etc., may be done automatically in the regular course of writing numbers, so as to relieve the operator of the necessity of printing commas or periods, or operating a space key to effect such spacing.

20 In my co-pending application, Serial No. 79,969, filed February 23, 1916 (now Patent No. 1,282,823, dated October 29, 1918), and in the co-pending application of Andrew W. Steiger, Serial No. 87,672, filed March 30, 25 1916, is disclosed mechanism for effecting such automatic spacing. Said mechanism includes an escapement wheel, which cooperates with a fixed dog and a loose dog supported on a dog rocker, the latter controlled by the character keys, to effect letter-feed movements of the carriage. In order to cause a double-space movement of the carriage at a point where it is desired to space between figures, a stop member, which 30 35 controls the pivoted dog, is shiftable into a position to permit a greater throw of the dog, so that a double-space movement of the escapement wheel is permitted.

The present invention, as herein shown, 40 is applied to a combined typewriting and computing machine of the type shown in the application of Henry L. Pitman, Serial No. 24,390, filed April 28, 1915, wherein the totalizer is connected to the platen carriage, to 45 travel therewith, and is adjustable to different positions along the carriage, to shift the computing zone. The totalizer may comprise a series of computing wheels which during the travel of the carriage through the 50 computing zone are brought successively into coöperative relation to a master wheel con-

trolled by the numeral keys, and operable when a numeral key is struck, to run up the corresponding number on the totalizer.

An object of the present invention is to 55 control the double-spacing mechanism from the totalizer and cause the double-spacing to be effected automatically at the points determined by the position of adjustment of the totalizer along the carriage. In carrying out the invention, the totalizer may be provided with a series of tappets, arranged to coöperate with means on the carriage, connected to operate the shiftable stop member to effect double-space letter-feed movements 60 65 of the carriage. The tappets are so positioned that the double spacing will be automatically effected at the desired points. As shown, a bell-crank on the machine frame, in the path of the tappets on the totalizer, 70 is operated by the tappets and is connected through a system of linkages to the shiftable stop member controlling the escapement dog. A non-add or disconnect key may be provided to prevent operation of the computing mechanism when the numeral keys 75 are struck, and means may be provided for taking the double-spacing mechanism out of the control of the tappets when this non-add key is operated. Such means may comprise a slot-and-pin connection in said system of linkages, and means, operated by the non-add key, to shift a link carrying said pin, into position to cause the pin to work idly in said slot, whereby said shiftable stop 80 85 member may remain idle. Means may also be provided to prevent operation of the double-spacing mechanism when the usual shift key is operated, to permit printing with the upper-case characters. Means for 90 rendering the computing mechanism inoperative by the numeral keys, when a shift key is depressed, may be similar to that disclosed in the application, Serial No. 24,390, above referred to; and the means for preventing operation of the double-spacing mechanism, while the shift key is depressed, 95 may comprise connections extending from the platen-shifting frame, for shifting the link and pin, above referred to, to idle position. In other words, the slot-and-pin connection for disabling the double-spacing 100

mechanism is controlled both by the non-computing key and the space-shifting key.

Other features and advantages will hereinafter appear.

5 In the accompanying drawings,

Figure 1 is a transverse vertical section of the machine, some of the parts being broken away, and others being omitted.

10 Fig. 2 is a skeleton perspective view of my invention, showing the tappets on the totalizer that engage with a lever connected to a shiftable stop member, which limits the variable movement of the loose dog.

15 Fig. 3 is a fragmentary front elevation of the typewriter escapement, and shows the parts set so as to allow the typewriter carriage to be moved single letter-space distances.

20 Fig. 4 is a similar view, with the escapement dogs rocked rearwardly.

Fig. 5 is a view similar to Fig. 4, except that the escapement is set for double spacing.

25 Fig. 6 is a diagrammatic view of the double-spacing mechanism and the various controlling means therefor.

30 The typewriting machine, except some of the escapement mechanism which will hereinafter be clearly described, is of the usual Underwood construction, in which the numeral keys 11 and alphabet keys 12, when depressed, move the key levers 13 and 14, and rock bell-cranks 15 to swing the type bars 16 on their fulcrum rod 17, upwardly and 35 rearwardly, causing types 18 and 19 to print against a platen 20 on a shaft 21, which is rotatably mounted in a platen frame 22.

35 The platen 20 is shiftable from lower to upper case, so as to allow either one of the 40 types 18 or 19 to print, and is guided in its case-shifting movements by links 23 on a rock shaft 24. A shift key 25, when depressed, moves the lever 26 provided with an arm 27, and the latter rocks a shift frame 45 28 about its pivot 29 to elevate a shift rail 30, carried thereby, thus moving the platen frame 22 upwardly. Connection between the shift rail 30 and platen frame 22 is 50 made in the usual manner by a roller 31 and a finger 32 carried by a bar 33 on the platen frame.

55 For propelling the carriage, there is provided a spring drum 36 which is connected to the typewriter carriage 37 by means of a strap 38.

To control the letter-feed movements of the typewriter carriage, it is provided with a rack 41 pivoted thereto at 42, and meshing 60 with a pinion 43 to rotate an escapement wheel 44, provided with teeth 45. The pinion 43 is connected to the escapement wheel 44 by the usual one-way driving pawls 46. This escapement wheel cooperates with a loose dog 47 and a fixed dog 48 mounted on 65 the carrying frame or dog rocker 49,

The typewriter escapement, except the double spacing feature herein described, is in many respects like that described in the patent to Rice et al., No. 769,804, dated September 13, 1904, and is operated in the 70 following manner.

Each type bar 16 provided with a heel 53 which, when the type bar is swung to printing position, moves the universal bar 54 rearwardly against the tension of a return 75 spring 55 (Fig. 2), and rocks the dog carrier against the tension of the usual Underwood return spring 56 (Fig. 3), shown in said patent. The spring 56 serves the double function of swinging the loose dog on its 80 pivot 57 when the upper part of the dog carrier is moved rearwardly, and returning the dog carrier to normal position. During the operation of the type bars 16, the dog rocker 49 is caused to vibrate transversely 85 of the escapement wheel 44, thus bringing the teeth of the escapement wheel 44 into coöperation alternately with the loose and fixed dog. When the dog carrier is moved rearwardly, the loose dog 47 is disengaged 90 from a tooth 45 of the escapement wheel after the fixed dog 48 has moved rearwardly into position to engage said tooth and hold the escapement wheel. The loose dog 47 when thus disengaged is permitted under 95 the influence of spring 56 to move to a position where it is arrested by a stop 58. When the dog rocker is brought back to normal position, the loose dog will be brought into the path of the next succeeding 10 tooth 45 of the escapement wheel 44 and the fixed dog will be withdrawn from the path of the wheel. The wheel being now free, is rotated, causing said succeeding tooth 45 to swing the loose dog about its pivot 10 57 back to normal position against a stop 50 on the dog carrier 49, thereby arresting the carriage after a letter-space movement thereof.

The computing machine comprises one or 11 more movable totalizers 61, arranged to travel with the typewriter carriage 37, at the front of the machine, on rollers 62 and 63 coöperating with a guide rail 64 supported by the machine frame 65. The totalizer 61 is connected to the typewriter carriage 37 by a latch 66 engaging with any one of several notches in a notched bar 67 on the typewriter carriage. The totalizer is provided with the regular dial wheels 68 12 and computing wheels 69, so that the position of the totalizer selects the computing zone.

When an adding zone is reached during the travel of the typewriter carriage, the 13 computing wheels are brought into coöperative relation, one at a time, with the master wheel 73 which is rotated through variable angular distances according to digits printed and acts as a denomination-selector in the 14

computing zone selected by the position of the totalizer.

To drive the master wheel, there is provided a bail or bar 74 having downwardly extending arms 75, one at each side of the machine, pivotally mounted (as shown in said application of Pitman No. 24,390) on a rock shaft 76, and moved through different angular distances by differentiators 77. Each numeral-key lever 13 is provided with a differentiator 77, the cam slots 78 in the differentiators 77 being of different shapes to effect the variable movements of the bar 74. When the machine is set to compute, the variable movements of the bar 74 are transmitted to a lever 79, secured to the rock shaft 76, by means of an intermediate lever 80, the latter being under constant tension of a spring 81 to hold the slotted portion 82 of the lever 80 against a pin 83 projecting from one of the arms 75. When any numeral key is depressed it rocks the levers 74, 75, with the result that the lever 80 gives an end thrust. By this the lever 79 is rocked, and pulls the link 84 downwardly to swing an arm 85 on a rock shaft 86 to move a second arm 87 on the rock shaft 86, and drive a rack 88 by means of a link 89. The forward movement of the rack 88 rotates a pinion 90 and a gear wheel 91, both pinion and gear wheel being secured to a shaft 92 which is slid able, by an add or a subtract key arranged on the front of the machine (not shown in the drawings), to bring the gear wheel 91 into mesh with an intermediate pinion 93, or a pinion 94 mounted on a shaft 95.

It should be understood that the master wheel 73 and the pinion 94 are both secured to the shaft 95, that the pinion 93 is constantly in mesh with the pinion 94, and that the gear wheel 91 is so arranged that it can be in mesh with either one of said pinions, but only one at a time. When the machine is set for addition, the gear wheel 91 meshes with the pinion 94, and movement is transmitted to the master wheel directly from the gear wheel 91 through the pinion 94, but when the machine is set for subtraction, motion is transmitted from the gear wheel 91 to the pinion 93 and then to pinion 94, to rotate the master wheel in the opposite direction.

To prevent accidental displacement between the master wheel 73 and the computing wheel 69 during the computing operation, there is provided a locking lever 96 on a shaft 97, the lever engaging in one of a series of slots 98 in a bar 99 on the totalizer 61 at each computing operation, said lever being operated in the usual way (not shown in the drawings).

To disconnect or, in other words, to make the computing mechanism inoperative when writing numbers in a computing zone, I

have provided a disconnect key 101 which, when thrown forward, about its pivot 102, moves a link 103 to rock a lever 104, an arm 105 on said lever moving the intermediary lever 80 against the tension of the spring 81, so that the slotted portion becomes disengaged from the pin 83. Thus it will be seen that if a numeral lever is now depressed, the bar 74 will be moved forwardly, but this motion will be ineffective to move the train of connections to the master wheel, since the connection between said bar and intermediate lever 80 has been broken.

To disconnect the computing machine during the shifting operation of the platen, which is necessary when the numeral type bar is provided with a numeral and other character of type, so as to prevent computing when the numeral keys are operated while the carriage is in a computing zone and the platen shifted to upper case, the lever 104 is connected to the shift frame 28 by means of a link 106. Thus, when the platen is shifted to upper case position, the platen shift frame 28 is rocked as hereinbefore explained and through the link 106 and lever 104, moves the intermediate lever 80 out of co-operative relation with the pin 83. To prevent shifting the shift frame 28 when the disconnect key 101 is shifted, I have provided a lost motion connection 108 between the frame 28 and link 106. A similar connection 107 between the link 103 and disconnect key 101, permits the latter to remain at rest when the frame 28 is shifted.

The means for effecting double space movements of the typewriter carriage at predetermined positions during its travel, will now be described. The stop 58 which normally controls the swinging escapement dog 47, as heretofore described, is carried on a shiftable stop member or lever 110 pivoted on a stud 111 on the escapement bracket 112, the lever being held in position lengthwise of the stud by nuts 113, 114. A second stop 115 on said lever is so positioned that when the lever is rocked from the Fig. 4 position to the Fig. 5 position, the stop 115 is brought into the path of the dog 47, while the stop 58 is moved out of the path of a pin 117 on the dog, permitting the dog (when released from the escapement wheel) to swing to the left until arrested by striking the stop 115. If the dog rocker 49 is now rocked to disengage the fixed dog 48 from the escapement wheel, the latter is permitted a double space movement, as one tooth 45 has been skipped by the pivoted dog.

The stop lever 110 is held in its normal position by a spring 116, but is rocked against the tension of said spring to the double spacing position by the following means. The totalizer 61 is provided with tappets 121 arranged at the upper part of the bar 99 in position to clear the lever 96 as

the latter moves along said bar during the travel of the typewriter carriage. A bell crank lever 122 is loosely mounted to swing on the rock shaft 97 and comprises an upright arm which extends into the path of the tappets 121 to be cammed rearwardly by the tappets as the carriage approaches positions at which it is desired to effect double space letter-feed movements.

10 When the bell crank 122 strikes a tappet 121 it is rocked to move downwardly a link 123 connected to the horizontal arm of the bell crank. Said link is connected with the forward end of a rock arm 124 fixed to a rock shaft 127 pivoted on the machine frame 65, to which rock shaft is also fixed a rearwardly extending rock arm 125. The downward movement of the link 123 operates through said rock arms and a link 126 connecting the arm 125 to the stop lever 110, to swing the latter to the Fig. 5 position, permitting a double space movement of the escapement.

25 The dial wheels 68 are arranged in groups as shown in Fig. 2, with a space provided between the thousands and the hundreds wheel, and also between the units and cents wheel. There are as many slots 98 in the bar 99, as there are dial wheels, the locking 30 lever 96 engaging in a slot while the corresponding dial wheel is being rotated. Thus it will be seen that the slots 98 are arranged in groups which correspond to the grouping of the dial wheels 68.

35 To explain more clearly the double space movements of the typewriter carriage, let it be assumed that the totalizer has reached the ten thousands position, the totalizer being moved by the carriage. In this position one 40 of the tappets 121 is ready to engage the lever 122. If we now print in this position, the escapement mechanism will operate as usual to permit the carriage to advance a single letter-space distance. This movement 45 of the carriage, however, will cause the tappet 121 to swing the lever 122 on the rock shaft 97, and through the train of connections hereinbefore described, shift the stop 50 115 to the Fig. 5 position, so that on the next depression of a numeral key (the carriage now being in the thousands position), the loose dog 47 will be permitted to move to the position shown in Fig. 5, where it is arrested by the stop 115. When the dog 55 rocker is allowed to return to normal position, the loose dog will move back of the adjacent tooth 45 and engage with the next tooth, permitting a double space movement of the escapement wheel, and the carriage 60 will be fed two letter space distances. Automatic double spacing is in like manner effected at the decimal point position, and at any other desired points in the computing zone by correspondingly located tappets 121.

65 To make the double spacing ineffective,

which is desirable when the platen is shifted to upper case position, or when the computing machine is set to disconnect, I have found it advantageous to provide a slot 131 in the arm 124, and connect the link 123 to the 70 arm 124 by a headed pin 132 which is slideable in the slot by means of a link 133 connected to an arm 134 extending from a rock shaft 135. Both the lever 104 and the arm 134 are secured to the rock shaft 135, the 75 arm 134 being near the middle of the machine. Thus it will be seen that when the lever 104 is moved by the disconnect key 101 or by the shift frame 28, the link 133 will be moved forwardly to bring the pin 132 to 80 the vertical portion of the slot 131. When the pin is in this position, the link 123 will be ineffective to move the arm 124, for although the lever 122 is actuated by the tappets 121, it will be ineffective to shift the 85 stop member 110 as the pin 132 will move up and down idly in the vertical portion of the slot 131. A light spring 136 is provided to hold the link 123 up in its normal position when the pin 132 is shifted to the vertical 90 part of the slot 131.

Variations may be resorted to within the scope of the invention, and portions of the improvements may be used without others.

Having thus described my invention, I 95 claim:

1. In a combined typewriting and computing machine, the combination of a typewriter carriage, means for propelling said typewriter carriage, reciprocating escapement devices which ordinarily permit the carriage to move single letter space distances, a totalizer arranged to travel with the typewriter carriage, and means controlled from said totalizer for allowing the 100 typewriter carriage to move more than a single letter space by a single reciprocation of said escapement devices.

2. In a combined typewriting and computing machine the combination of a typewriter carriage, means for propelling said typewriter carriage, reciprocating escapement devices which ordinarily permit the carriage to move single letter space distances, a machine frame, a totalizer arranged to travel with the typewriter carriage, a series of tappets on the totalizer, and a co-operating member movably mounted on the machine frame in the path of the tappets and operated thereby, and means whereby the movement of said member sets said escapement devices to permit the carriage to move more than a single letter space distance by a single reciprocation of said escapement devices.

3. In a combined typewriting and computing machine, the combination of a typewriter carriage, a totalizer, means for propelling said carriage, reciprocating escapement devices including a fixed and a loose 130

- dog, and means with which said loose dog coöperates to ordinarily permit single letter space movements of the carriage and to effect double space movements at predetermined positions in the travel of said typewriter carriage, said means being automatically shiftable and controlled from the totalizer during the travel of the typewriter carriage.
- 10 4. In a combined typewriting and computing machine, the combination of a typewriter carriage and a totalizer arranged to travel therewith, means for propelling said typewriter carriage, a variable feed escapement which normally allows the carriage to be fed a single letter space distance at each operation, said escapement including an escapement wheel, a dog rocker, a fixed and a loose dog carried by the dog rocker, a plurality of stops for said loose dog, and means for shifting said stops alternatively into coöperative relation with said loose dog, said shifting means being controlled from said totalizer.
- 15 5. In a combined typewriting and computing machine, the combination with a carriage and driving means therefor, of an escapement mechanism controlling the letter feed movements of said carriage, said mechanism comprising a wheel, a fixed dog and a loose dog coöperating with said wheel, a movable stop member adapted to control the throw of said loose dog, a totalizer mounted to travel with the carriage, and means for moving said stop member to effect an extra throw of said dog in writing a digit immediately at the left of a pointing off space, said means being controlled from said totalizer.
- 20 6. In a combined typewriting and computing machine, the combination with a carriage, of an escapement wheel for said carriage, a loose dog for permitting said escapement wheel to be fed, a movable stop member controlling the throw of said dog, a totalizer, and means for selectively controlling said movable stop member, said means being controlled from said totalizer.
- 25 7. In a computing machine, a totalizer comprising computing wheels arranged in groups with a space between said groups, a master wheel, means for bringing said computing wheels, one at a time, and the master wheel into coöperative relation with each other, reciprocating escapement devices to permit a step by step relative movement between said master wheel and said computing wheels, a series of tappets which are connected to said totalizer to bear a fixed relation with reference to the computing wheels, a coöperative member engaging with said tappets for controlling said escapement devices to cause them by a single reciprocation to effect a greater relative movement between said master wheel and comput-

ing wheels when the space is reached between said groups of computing wheels.

8. In a combined typewriting and computing machine, the combination of a carriage, an escapement wheel normally holding said carriage, a loose dog for feeding said escapement wheel and normally holding it, selective means for controlling said dog to permit said escapement wheel to be fed by said dog either one or two letter spaces, a totalizer, and means actuated thereby to operate said selective means and thereby cause said loose dog to feed the carriage two letter spaces.

9. In a combined typewriting and computing machine, the combination of a carriage, a variable feed escapement for said carriage, a totalizer traveling with said carriage, means controlled from said totalizer for permitting double space movements at predetermined positions in the travel of said carriage, computing mechanism, keys controlling said mechanism, means for taking said computing mechanism out of the control of said keys, and means for rendering said double space permitting mechanism ineffective when said computing mechanism is out of the control of said keys.

10. In a combined typewriting and computing machine, the combination of a carriage, a variable feed escapement for said carriage, a totalizer, means controlled from said totalizer for effecting double space movements at predetermined positions in the travel of said carriage, computing mechanism, means for disconnecting said computing mechanism, and means for providing a lost motion connection between the totalizer and said double space determining mechanism to render said double space escapement mechanism ineffective when the computing mechanism is disconnected.

11. In a combined typewriting and computing machine, the combination of a carriage, a variable feed escapement for said carriage, a totalizer, means controlled from said totalizer for effecting double space movements of the carriage at determined positions in its travel, said means comprising a bell crank connected to a lever of the first order by a link, and a shiftable stop member connected to said lever by a second link, computing mechanism, means for disconnecting said computing mechanism, and means providing a lost motion connection between one of said links and said lever to render said shiftable stop member inoperative when said computing mechanism is disconnected.

12. In a combined typewriting and computing machine, the combination of a carriage, a variable feed escapement for said carriage, a totalizer, means controlled from said totalizer for effecting double space movements of the carriage at determined

positions in its travel, said means comprising a bell crank connected to a lever of the first order by a link, and a shiftable stop member connected to said lever by a second link, computing mechanism, means for disconnecting said computing mechanism, and means for rendering said shiftable stop member inoperable, said means comprising a connecting rod between one of said links and the disconnecting means, the link connected to the lever of the first order being provided with a pin which is shiftable to the vertical portion of a slot in said lever, so that the pin will move idly in said slot should the link be operated.

13. In a combined typewriting and computing machine, the combination of a carriage, a variable feed escapement for said carriage, a totalizer, means controlled from said totalizer for permitting double-space movements of and at predetermined positions in the travel of said carriage, and means for rendering said double-space permitting means ineffective.

14. In a combined typewriting and computing machine, the combination of a carriage, a variable feed escapement for said carriage, a totalizer, means controlled from said totalizer for effecting double-space movements of and at predetermined positions in the travel of said carriage, a train of linkages between the totalizer and said double-space permitting means, and means for providing a lost motion in said train of linkages to render said double-space permitting means ineffective.

15. In a combined typewriting and computing machine, the combination of a carriage, an escapement for said carriage, a totalizer traveling with said carriage, a double-space permitting device controlled from said totalizer, a case-shift key, and means controlled from said case-shift key for rendering said double-space permitting device ineffective.

16. In a combined typewriting and computing machine, the combination of a carriage, an escapement for said carriage, a totalizer adjustably positioned to select a computing zone, a double-space-permitting device for said carriage, means controlled by said totalizer for rendering said double-space-permitting device effective, a case-shift key, a disconnect key for the computing machine, and means controlled from the case-shift key and the disconnect key for rendering the double-space permitting device ineffective.

17. In a combined typewriting and computing machine, the combination with a carriage and driving means therefor, of escapement mechanism controlling the letter-feed movements of the carriage, a totalizer connected to travel with the carriage, numeral keys for printing numerals and controlling

said escapement mechanism to effect letter-feed movements of the carriage, computing mechanism operated by the numeral keys for running up on the totalizer numbers corresponding to those of the operated keys, and a double-spacing means controlled from said totalizer and operable automatically to effect a double-space letter-feed movement of the carriage when the totalizer reaches a predetermined position in the computing zone, to thereby point off or space between figures at a corresponding point in the number being written.

18. In a combined typewriting and computing machine, the combination with a carriage and driving means therefor, of escapement mechanism controlling the letter-feed movements of the carriage, a totalizer connected to travel with the carriage, numeral keys for printing numerals and controlling said escapement mechanism to effect letter-feed movements of the carriage, computing mechanism operated by the numeral keys for running up on the totalizer numbers corresponding to those of the operated keys, a double-spacing means controlled from said totalizer and operable automatically to effect a double-space letter-feed movement of the carriage when the totalizer reaches a predetermined position in the computing zone, to thereby point off or space between figures at a corresponding point in the number being written, a disconnect key operable to take the computing mechanism out of the control of the numeral keys, and means controlled by said disconnect key for silencing the double-spacing means.

19. In a combined typewriting and computing machine, the combination with a carriage and driving means therefor, of escapement mechanism controlling the letter-feed movements of the carriage, a totalizer connected to travel with the carriage, numeral keys for printing numerals and controlling said escapement mechanism to effect letter-feed movements of the carriage, computing mechanism operated by the numeral keys for running up on the totalizer numbers corresponding to those of the operated keys, a double-spacing means controlled from said totalizer and operable automatically to effect a double-space letter-feed movement of the carriage when the totalizer reaches a predetermined position in the computing zone, to thereby point off or space between figures at a corresponding point in the number being written, a case shift key, and means controlled thereby for silencing said double-spacing means.

20. In a combined typewriting and computing machine, the combination with a traveling typewriter carriage, of a totalizer adjustable relatively to said carriage, an escapement device for said carriage, typewriter numeral keys adapted to write upon

said carriage, and to effect computation of digits in said totalizer, differential-throw means universal to said keys by which said computation is effected, means whereby said 5 escapement device may feed said carriage a double letter-space, connections whereby said totalizer automatically makes said double-letter-space means effective at pointing-off places, means for making said differential- 10 throw means ineffective to compute, and connections whereby said double-feeding means is automatically made ineffective when the differential-throw means is made ineffective to compute.

15 21. In a combined typewriting and computing machine, the combination with a typewriter carriage, of a rack bar adapted to travel with said carriage, escapement devices normally feeding said carriage single letter-space distances, a totalizer adapted to be adjustably set along said rack bar, means effective to cause said escapement devices to feed said carriage a double letter-space, and an extension of said totalizer adapted to selectively cause said last-named means to become effective.

20

25

22. In a combined typewriting and computing machine, the combination with a typewriter carriage, of a rack bar adapted a
30 to travel with said carriage, escapement devices normally feeding said carriage single letter-space distances, a totalizer adapted to be adjustably set along said rack bar, means effective to cause said escapement devices to
35 feed said carriage a double letter-space, a dog for operating said means, and tappets concealed by said totalizer but forming part thereof for operating said dog to cause a double letter-space movement of said carriage.
40

23. In a combined typewriting and computing machine, the combination with a typewriter carriage, of a totalizer adjustable relatively to said carriage, said totalizer including a series of wheels, denomination-selecting means to select said wheels as determined by the adjustment for relative co-operation of the carriage, totalizer, and selecting means, numeral keys, key-actuated means for writing digits spaced apart at pointing-off places and for effecting computation in said totalizer, key-controlled escapement devices to effect the travel of said carriage, and means controlled by the relative positioning of said denomination-selecting means and said totalizer for effecting at each of said pointing-off places a double feeding of said carriage for a single operation of said escapement devices.

30 24. In a combined typewriting and computing machine, the combination with a traveling typewriter carriage, of a totalizer adjustable relatively to said carriage, a platen forming part of said carriage, a denomination-selector, wheels forming part of

35

said totalizer adapted to be selected by said selector in columns determined by the adjustment for relative coöperation of the carriage, totalizer and selector, typewriter numeral keys adapted to write upon said platen 70 digits spaced apart at pointing-off places, and to effect computation of said digits in said totalizer, escapement devices controlled by said keys to effect the travel of said carriage in printing the digits and selecting the 75 wheels, means to enable a single operation of the escapement devices to effect a double feeding of said carriage, connections automatically made effective by said adjustment for determination of the computing zone, for 80 making said double-feeding means effective at every pointing-off place between digits computed in said totalizer, a case-shift adapted to cause the keys to selectively write in one of two cases, and means for making 85 said double-feeding means ineffective by operation of said case-shift.

25. In a combined typewriting and computing machine, the combination with a traveling typewriter carriage, of a totalizer 90 adjustable relatively to said carriage, a platen forming part of said carriage, a denomination-selector, wheels forming part of said totalizer adapted to be selected by said selector in columns determined by the adjustment for relative coöperation of the carriage, totalizer and selector, typewriter numeral keys adapted to write upon said platen digits spaced apart at pointing-off places, and to effect computation of said digits in said totalizer, escapement devices controlled by said keys to effect the travel of said carriage in printing the digits and selecting the wheels, means to enable a single operation of the escapement devices to 105 effect a double feeding of said carriage, connections automatically made effective by said adjustment for determination of the computing zone, for making said double-feeding means effective at every pointing-off place between digits computed in said totalizer, a device for making said numeral keys ineffective on said wheels, and a connection whereby said last-named device makes said double-feeding means ineffective. 110 115

26. In a combined typewriting and computing machine, the combination with a traveling typewriter carriage, of a totalizer adjustable relatively to said carriage, a platen forming part of said carriage, a denomination-selector, wheels forming part of said totalizer adapted to be selected by said selector in columns determined by the adjustment for relative coöperation of the carriage, totalizer and selector, typewriter numeral keys adapted to write upon said platen digits spaced apart at pointing-off places, and to effect computation of said digits in said totalizer, escapement devices controlled by said keys to effect the travel of said carriage, 120 125 130

- riage in printing the digits and selecting the wheels, means to enable a single operation of the escapement devices to effect a double feeding of said carriage, connections automatically made effective by said adjustment for determination of the computing zone, for making said double-feeding means effective at every pointing-off place between digits computed in said totalizer, a device 5 for making said numeral keys ineffective on said wheels, a connection whereby said last-named device makes said double-feeding means ineffective, a case-shift for making said keys effective to write selectively in one 10 of two cases, and means whereby said case-shift operates said last-named device.
27. In a combined typewriting and computing machine, the combination with a traveling typewriter carriage, of a totalizer 20 adjustable relatively to said carriage, a platen forming part of said carriage, a denomination-selector, computing wheels forming part of said totalizer adapted to be selected by said selector in columns determined by the adjustment for relative 25 cooperation of the carriage, totalizer and selector, typewriter numeral keys adapted to write upon said platen digits spaced apart at pointing-off places, and to effect computation of said digits in said totalizer, escapement devices controlled by said keys to effect the travel of said carriage for printing the digits and selecting the wheels, a lever 30 shiftable to enable a single operation of the escapement devices to effect a double feeding of said carriage, a link for operating said lever, a pin on said link normally engaging a slot in said lever, said slot comprising an extension to permit the idle operation of the link, connections automatically 35 made effective by the adjustment for said determination of the computing zone for making said link effective on said lever, to make the double-feeding lever effective at 40 every pointing-off place between digits computed in said totalizer, a device for making said keys ineffective to compute, and means whereby said last-named device is effective to shift said link to make it idle with respect 45 to said lever.
28. In a combined typewriting and computing machine, a typewriter carriage, a carriage-feed mechanism including escapement devices to permit the carriage to move 50 single letter-space distances, a totalizer connected with the typewriter carriage to travel therewith, and means controlled by said totalizer to modify the action of the escapement to cause feed movements of more than 55 a single letter-space.
29. In a combined typewriting and computing machine, the combination of a typewriter carriage, a totalizer connected to travel therewith, an escapement feed for said 60 carriage including a fixed and a loose dog,

controlling means for said loose dog to cause single and double space movements of said carriage, and totalizer-actuated means to operate said controlling means to cause double-space movements of said carriage. 70

30. In a combined typewriting and computing machine, the combination of a carriage, a variable feed therefor, computing mechanism including a totalizer connected to move with said carriage, totalizer-controlled means to cause double space movements of said carriage, and means for rendering ineffective concomitantly said computing mechanism and said means to cause double space movements. 75

31. In a combined typewriting and computing machine, the combination of a carriage, an intermittent feed therefor, a totalizer connected to move with said carriage, and totalizer-controlled means for varying 80 the movement of said intermittent feed.

32. In a combined typewriting and computing machine, the combination of printing means, a typewriter carriage, a step-by-step feed to move said carriage relatively to said 85 printing means, a totalizer movable with said carriage, totalizer-actuated means for varying the movement of said feed to effect double space movements of said carriage, and means for rendering said totalizer-actuated 90 means ineffective to vary the motion of said feed. 95

33. In a combined typewriting and computing machine, the combination of a platen, a carriage for said platen, a step-by-step 100 feed device for said carriage, a totalizer movable with said carriage, totalizer-actuated means for causing double feed movements of said feed device, a case-shift device including a case-shift key, and means actuated by the case-shift device for rendering 105 said totalizer-actuated means ineffective.

34. In a combined typewriting and computing machine, computing mechanism, a typewriter carriage, a carriage-feed to give 110 letter-space movements, means controlled by the computing mechanism for causing double space movements of said carriage, a case-shift, and case-shift-operated means for rendering ineffective said means for causing 115 double space movements of the carriage.

35. In a combined typewriting and computing machine, the combination of a carriage, means for propelling said carriage, a variable feed escapement for said carriage, means for permitting double-space 120 movements, in columnar positions, of said carriage, a totalizer adapted to be set at any columnar position in which the double-space movements of the carriage are to be effected, 125 and means associated with the totalizer for rendering said double-space-permitting means effective.

36. In a combined typewriting and computing machine, the combination of a car- 130

riage, means for propelling said carriage, a variable feed escapement for said carriage, means for permitting double-space movements in columnar positions of said carriage,
5 a totalizer adapted to be set at any columnar position in which the double-space movements of the carriage are to be effected, and

means engaged by said totalizer, for rendering said double-space-permitting means effective.
